Arthur F. Jacobs, Los Angeles, Calif., assignor to
Modeline Company of California Inc., Los Angeles,
Calif., a corporation of California

Filed July 17, 1959, Ser. No. 56,815

Term of patent 14 years

(Cl. D48—20)

Fig. 1 is a side elevational view of a lamp base, showing my new design;

Fig. 2 is an elevational view of the lamp base taken from the right of Fig. 1;

Fig. 3 is a rear elevational view of the same base;

Fig. 4 is an elevational view taken from the left of Fig. 1;

Fig. 5 is a top plan view of the base; and

Fig. 6 is an enlarged fragmentary sectional view taken on line 6—6 of Fig. 1.

The shade and standard are shown only in broken lines in Fig. 1 for illustrative purposes only.

I claim:

The ornamental design for a lamp base or similar article, as shown and described.
